DESIGN FOR A NEEDLE WORKER'S UTILITY HOLDER

Minnie Federman Corder, New York, N. Y.

Application March 18, 1943, Serial No. 109,777

Term of patent 14 years

To all whom it may concern:

Be it known that I, Minnie Federman Corder, a citizen of the United States, residing in New York city, in the county and State of New York, have invented a new, original, and ornamental Design for a Needle Worker's Utility Holder, of which the following is a specification, reference being had to the accompanying drawing, forming a part thereof.

In the accompanying drawing

Fig. 1 is a perspective view of a needle worker's utility holder, showing my new design,

Fig. 2 is a top plan view thereof; and

Fig. 3 is a right end elevational view thereof.

I claim:

The ornamental design for a needle worker's utility holder, as shown.

MINNIE FEDERMAN CORDER.
